UNITED STATES PATENT OFFICE.

MATTHEW RANDALL, OF CHICAGO, ILLINOIS.

DESIGN FOR A TOY AEROPLANE.

Application filed October 30, 1928. Serial No. 28,694. Term of patent 7 years.

To all whom it may concern:

Be it known that I, MATTHEW RANDALL, a citizen of the United States, residing at Chicago, in the county of Cook and State of Illinois, have invented a new, original, and ornamental Design for a Toy Aeroplane, of which the following is a specification, reference being had to the accompanying drawing, forming a part thereof.

The figure is a rear perspective view of a toy aeroplane, showing my new design.

I claim:—

The ornamental design for a toy aeroplane, as shown.

In testimony whereof I affix my signature.

MATTHEW RANDALL.
